Inventor

Stengrim Alseth,

By
Geo. P. Kimmel. Attorney

UNITED STATES PATENT OFFICE.

STENGRIM ALSETH, OF MINNEAPOLIS, MINNESOTA.

PORTABLE MERRY-GO-ROUND.

Application filed February 17, 1921. Serial No. 445,694.

To all whom it may concern:

Be it known that I, STENGRIM ALSETH, a citizen of the United States, residing at Minneapolis, in the county of Hennepin and State of Minnesota, have invented certain new and useful Improvements in Portable Merry-Go-Rounds, of which the following is a specification.

This invention relates to a carrousel and more particularly to the class of portable merry-go-round.

The primary object of the invention is the construction of an apparatus of this character wherein the same is of such form and size that it may be placed either indoors or outdoors and may be positioned within a room so that the children may operate the same, levers being provided whereby the children may actuate the device from a seat, simulating hobby-horses or similar objects.

Another object of the invention is the provision of an apparatus of this character which is novel in construction so that the children may be afforded amusement in the use of the same and permit variation in the speed of travel of the merry-go-round at the option of the riders, the apparatus being of such design and size as to be easily transported and positioned in a comparatively small sized room without interfering with other play toys.

A still further object of the invention is the construction of a merry-go-round of the type above set forth wherein suitable provision is had for supporting the seats or hobby-horses from a central supporting post, anti-friction devices being provided to permit the merry-go-round to be easily operated with a minimum of effort and without resorting to the use of rollers or casters.

A still further object of the invention is the construction of an apparatus wherein the seats may be partly supported by suitable bracing means from a central pivot post including anti-friction means whereby the children may easily operate the apparatus by a pair of conveniently arranged levers connected to said post, the apparatus being constructed and arranged to be operated by children with a minimum of effort and which will not readily get out of order or require any particular care or attention.

A still further and very important object of the invention is the construction of a merry-go-round of the type above set forth which will be extremely simple in construc-

tion, comprising comparatively very few parts therefor, inexpensive to manufacture, neat and attractive in appearance, readily and easily operated, strong, durable and of such style and design that it simulates a portable toy capable of being transported from one position to another and adapted to be used either indoors or outdoors.

With these objects in view and others which will be suggested and manifest as the nature and purpose of my invention are revealed in the following specification and drawing, wherein I have shown but one form or embodiment thereof,

Figure 1 is a plan view of the merry-go-round,

Fig. 2 is a front elevation, and

Fig. 3 is a fragmentary view of the support for the central pivot post.

Referring now to the drawing where like parts designate the same parts in the specification, 5 designates the flooring or base of the merry-go-round suitably reenforced by cross pieces 6 at its center which supports the operating mechanism now to be described.

A vertically extending conoidal shaped skeleton support 7, in the form of a casting, is positioned centrally of the flooring or base and provides a support for a central pivot post 8 about which the merry-go-round is adapted to rotate. If desired the central support 7 may be cast with the flooring or separable therefrom and secured as at 9, thus forming a rigid supporting structure for the rotating element subsequently to be referred to. The support 7 terminates in a substantially circular head 10 which is provided with recesses for receiving an anti-friction element 11 which forms a bearing for a tapered cross piece which is adapted to revolve and rotate about the central supporting post 8. The said cross piece 11 which may be constructed of wood or similar material is provided with a central aperture for receiving the central post and has also secured thereto as at 12 the flange 13 of a bearing block 14 which overlies the head 10 and freely rotatable about the same as clearly indicated in Fig. 3.

The cross piece 11 tapers outwardly as shown at 15 and supports at its opposite ends a vertically positioned object simulating a hobby-horse or other rigid support 16 having the usual seat 17 to accommodate the children as is well understood. As shown

the vertical supports 16 may be formed integral with or separable from the cross piece and in order to brace the same and provide a rigid structure, I have provided suitable 5 angularly extending brace rods 18, 19 secured at 20 to the front and rear and beneath the supporting member 16, the upper terminals of said brace rods being secured to the flange 22 of a bearing block 23 positioned 10 on the central pivot post above referred to. Suitable anti-friction devices or ball bearings 24 are provided in recesses 25 at this point whereby the rotation of the cross piece and the support is easily effected.

15 From the above construction, it will be readily seen that I have provided suitable bearings in the upper and lower portion of the pivot post 8 to thus afford easy operation of the merry-go-round with a minimum of 20 effort without resorting to the use of casters or similar devices. A disk 27 provided with a central aperture is positioned on the top of the pivot post 8 and has secured thereto a pair of operating levers 28, 29 extending 25 outwardly and in proximity to the seat 17 whereby the said levers may be grasped by the children in operating the device. It will be noted that the reduced end 30 of the lever 28 lies beneath the said disk and that 30 the reduced similar end 31 of the other lever overlies the disk and is made secure thereto by a fastening nut 32 as clearly shown in Fig. 1 of the drawing. Within each of the reduced ends of the respective levers, there 35 are provided dogs 33 which are adapted to frictionally engage the periphery of the said disk as the levers are operated by the children to propel and rotate the apparatus about the central pivot post 8.

40 In the accompanying drawings, I have illustrated my invention embodied in one form by way of example, and which in practice has been found to be highly satisfactory in obtaining the desired results. It 45 will be obvious however that other embodiments may be adopted and that various changes in the details of construction may be resorted to by those skilled in the art without departing from the spirit and scope

of the invention. It is furthermore understood that the invention is not necessarily limited or restricted to the precise elements shown except in so far as such limitations are specified in the subject matter being claimed. 50

Having shown and described my invention what I now claim as new and desire to secure by Letters Patent of the U. S. is:—

In an apparatus of the class described, a base, a vertical support secured thereon centrally thereof and formed at its top with a bearing, a one-piece revolvable supporting member provided centrally with a depending bearing mounted on the bearing of said support, a vertically disposed stationary post secured centrally at its lower end to said base and extending up through said support and member and further projecting a substantial distance above said member, a carrier secured centrally to and extending 60 transversely of each end of said member and further projecting beyond each side of said member, an annular bearing integral with said post at a point in proximity to the upper end thereof, a block surrounding said 65 post, mounted on said annular bearing and formed at each side with a lateral flange, two pair of oppositely extending depending braces, the braces of each pair diverging with respect to each other from their upper to 70 their lower ends and connected at their upper ends to a flange and having angular lower terminal portions secured to the ends of a carrier, a friction disk fixedly secured to the top of said post, a pair of oppositely disposed 75 hand levers, each of said levers having an offset inner terminal portion of greater width than the width of the lever, said offset portions having their free ends loosely mounted on said post and arranged against 80 the upper and lower face of said disk, and friction dogs carried on the inner faces of said offset portions and engaging said disk to revolve said member.

In testimony whereof, I affix my signature hereto.

STENGRIM ALSETH.
